[57] CLAIM

The ornamental design for a housing for anti-theft detector, as shown and described.

DESCRIPTION

FIG. 1 is a perspective view of a housing for anti-theft detector showing my new design;

FIG. 2 is a front elevational view thereof;

FIG. 3 is a side elevational view thereof, with the opposite side being a mirror image;

FIG. 4 is a top plan view thereof; and,

FIG. 5 is a perspective view thereof, with the housing shown in an unassembled and open condition.

FIG. 1

FIG. 4

FIG. 2

FIG. 3

FIG. 5
